UNITED STATES PATENT OFFICE.

EDWARD V. ANDERSON, OF MONESSON, PENNSYLVANIA, ASSIGNOR OF ONE-HALF TO
CHARLES E. GOLDEN, OF CRAFTON, PENNSYLVANIA.

CUSHION-VALVE.

1,077,502.

Specification of Letters Patent. Patented Nov. 4, 1913.

Application filed February 1, 1911. Serial No. 608,058.

To all whom it may concern:

Be it known that I, EDWARD V. ANDERSON, a citizen of the United States, residing at Monesson, in the State of Pennsylvania, have 5 invented certain new and useful Improvements in Cushion-Valves, of which the following is a specification.

My invention relates to the general class of non-return or stop-valves and particularly to valves having means to cushion the 10 action to prevent sudden and violent motions, especially in the operation of closing.

I have illustrated the invention in the accompanying drawing in which—

15 Figure 1 is a longitudinal section of a casing containing a preferred form of the valve and Fig. 2 is a side elevation and partial section.

These figures show a casing 9 with a vertically arranged valve seat 10 and a disk valve 11 pivoted on a trunnion 12 by means of a rigidly attached arm 13. The cap 14 is for easy insertion of the valve. On the side of the casing 9 is a box 15 through which extends the trunnion 12, carrying rigidly thereon a cushioning wing 16, which closely fits the sector shaped boxing 15. The box 15 is filled with a fluid and in any motion of the valve 11, the vane 16 moves correspondingly and the action is therefore cushioned in either opening or shutting. The vane 16 is so arranged as to come into contact with its limiting wall at the same time that the valve disk 11 reaches its limiting position, whereby 30 to entrap the fluid and render the final motion of the valve necessarily slow as the fluid leaks under the wing 16. By reason of leak-

age along the opening by which the shaft 12 passes through the side of casing 9, the pressure of fluid in the box 15 remains normally 40 the same as that of the fluid in the casing. Thus the valve is caused to both open and close slowly, but without any permanent resistance to its remaining open. Water hammer or sudden closing is entirely prevented, 45 and in both cases the closing motion meets with an increasing retarding resistance as the valve approaches its seat.

Other advantages of the device will readily occur to those familiar with the art. 50

Having thus described my invention, and illustrated its use, what I claim is the following:

1. A direct seating valve having means to cushion its approach to its seat and also its 55 opening movement said cushioning means being designed to interpose increasing resistance as the valve approaches its limiting position.

2. The combination with a valve casing 60 and a valve therein, of a supplementary closed compartment on the casing, and a retarding vane located in said compartment and rigidly mounted on the same shaft with the valve, whereby to prevent sudden closing 65 of the valve, substantially as described.

In testimony whereof I have hereunto signed my name in the presence of the subscribed witnesses.

EDWARD V. ANDERSON.
